his Attorney.

UNITED STATES PATENT OFFICE.

ALEXANDER S. MATHERS, OF LOS ANGELES, CALIFORNIA.

TIE DEVICE.

1,423,133.

Specification of Letters Patent.

Patented July 18, 1922.

Application filed May 28, 1921. Serial No. 473,456.

To all whom it may concern:

Be it known that I, ALEXANDER S. MATHERS, a citizen of the United States, residing at Los Angeles, in the county of Los Angeles and State of California, have invented new and useful Improvements in Tie Devices, of which the following is a specification.

This invention has to do with a device for 10 tying or connecting members or objects together, and it is an object of the invention to provide a simple, effective, convenient device of this character.

Various devices heretofore provided and 15 used for holding objects together have either been more or less ineffective, complicated, inconvenient to manipulate, bulky, or ungainly. For instance nails, although simple and easy of manipulation are more or less ineffective in that they work loose and do not hold securely, screws although they hold 20 securely and do not readily work loose are more or less inconvenient to apply and remove, and clamp devices of various kinds 25 are characterized by being more or less complicated of construction and inconvenient to manipulate. The device of the present invention is extremely simple in construction and manipulation, is neat and sightly, 30 and is particularly effective.

A noteworthy feature of the invention is 35 the provision of a device of the character specified which is effective and is simple both in construction and manipulation. The device comprises only two parts both of which are of simple and inexpensive formation making the device inexpensive of manufacture. In operation the device can be very 40 easily and quickly arranged in position to be actuated and requires only one simple, easily 45 executed operation for its actuation. The device can be very easily and quickly detached from the objects held together by it and leaves the objects practically without 50 mutilation.

The device of the present invention is applicable for use in various arts and in a large variety of structures. For the purpose of describing a typical application of the 55 device and to thereby facilitate a clear and accurate understanding of the invention I herein describe in detail a form of the invention particularly adapted to hold together two members arranged together transversely of each other. In the following detailed description I refer to a bowling alley and to a

support for the bowling alley as two members or objects to be secured together by the present device. It will be understood, of course, that the device of the present invention is capable of considerable modification from that herein specifically pointed out and that it is not necessarily limited in application to any specific arrangement of members or class of structures.

The various objects and features of the invention will be best and more fully understood from the following detailed description of a typical embodiment of the invention throughout which reference is had to the accompanying drawings in which—

Fig. 1 is a transverse, sectional view of a bowling alley supported on a transverse support member and held to and in place on the support member by devices of the present invention; Fig. 2 is an enlarged plan view of one edge portion of the bowling alley at the support, showing in plan a device of the present invention holding the alley and support together, being a view taken as indicated by line 2—2 on Fig. 1; Fig. 3 is an enlarged side elevation of a portion of the alley at the support being a view taken as indicated by line 3—3 on Fig. 2; Fig. 4 is an enlarged transverse sectional view taken as indicated by line 4—4 on Fig. 3 showing the device of the present invention arranged in position ready to be actuated; Fig. 5 is a view similar to Fig. 4 showing the device of the present invention actuated and in position to solidly and securely hold the alley on and to the support; Fig. 6 is similar to Fig. 3 showing the device ready to be actuated; and Fig. 7 is a perspective view of the device provided by the present invention independent of any other parts.

Throughout the drawings numeral 10 designates a typical bowling alley mounted on a transverse support 11. The bowling alley 10 is of the usual laminated construction and has a flat finished top 12, a flat bottom 13 parallel with the top 12, and flat sides or edges 14 connecting the top 12 and bottom 13. The support 11, which is merely one of a plurality of supports arranged to carry the alley 10, is rectangular in cross sectional configuration and is arranged transversely under the alley 10 in engagement with the bottom 13. In structures of this character both parts, that is, the alley and the support, 110 are formed of wood, the alley usually being of hard wood such, for instance, as maple.

At each side of the alley 10 at the support 11 there is arranged a tie device 15 embodying the present invention. The tie devices, as illustrated in Fig. 1 are arranged in connection with the alley 10 and support 11 to solidly hold the alley and support firmly and securely together.

A device embodying the present invention comprises, generally, two members or legs 16 and 17 pivotally connected together at or near their inner ends by a suitable pivot pin 18. The legs 16 and 17 diverge outwardly from the point of pivotal connection and correspond with each other in every respect except that the inner end portion 19 of the leg 17 extends only to the point of pivotal connection between the two legs while the inner end portion 19 of leg 16 extends somewhat beyond the pivotal connection between the two legs. Although various means may be provided for pivotally connecting the inner end portions of the legs 16 and 17 it is preferred that a simple, inexpensive form of construction be employed, say for instance, that they be connected by a straight pivot pin 18 the ends of which are flattened or riveted over to form heads. The pivot pin 18 need not be removable as the practical use of the device does not require separation of the legs 16 or 17.

The outer end portions 20 of the legs 16 and 17 extend somewhat inwardly, or are at an angle to the inner end portions 19 of the legs. The angularity of the outer end portions 20, relative to the inner end portions 19, is preferably, although not necessarily, such that the end portions 20 are substantially parallel with each other when the inner end portions 19 form an angle of substantially 90° .

A wedge shaped projection 25 extends from the inner end of the leg 16 in a direction substantially transverse of the plane of the legs, or parallel with the axis of the pivot pin 18. In practice it is desirable to form the projection 25 integrally with the leg as such construction is simple, inexpensive and strong. The projection 25 is preferably comparatively broad and flat and is tapered outwardly, or is wedge shape, so that its outer edge 26 is sufficiently sharp to readily cut into wood or the like. The projection 25 extends from the leg 16 so that it is substantially horizontal in a transverse direction and extends outwardly and somewhat upwardly from the end of leg 16 in a longitudinal direction when the legs are arranged in a vertical plane with their outer portions 20 arranged vertically. When the outer portions 20 of the legs are in this last mentioned position, that is, when they are substantially vertical the inner portions 19 of the legs extend upwardly and inwardly from the outer portion 20 to the point of pivotal connection at angles of substantially 45° .

At the outer end of each outer portion 20 there is a wedge shaped projection 30. The projections 30 on the two portions 20 face each other, or face inwardly, in the manner clearly shown in the drawings. The projections 30 on the two portions 20 in facing or extending generally toward each other extend in directions substantially at right angles to the direction which the projection 25 extends. The projections 30 extend in directions at right angles to the axis of the pivot pin 18 while the projection 25 extends substantially parallel with the pivot pin 18. The projections 30 are tapered or wedge shaped so that their outer edges 31 are sufficiently sharp to readily cut into wood, or the like. When the legs are positioned so that the outer portions 20 are substantially parallel the projections 30 extend inwardly and somewhat downwardly. The shape of the projections 30 and the relation that they bear to each other and to the various other parts of the device will be clearly and readily understood from inspection of the drawings. It is preferred that the projections 30 be integral with the legs.

In applying the device to two members, say for instance to the alley 10 and support 11, the legs 16 and 17, are swung apart so that they form an angle of considerably more than 90° and until their outer parts 20 can be placed over the support 11 so that the edges 31 of the projections 30 engage the sides of the support 11 at opposite points in the manner clearly illustrated in Fig. 6 of the drawings. The device is thus placed over the support 11 with the projection 25 facing the side 14 of the alley 10, and so that the legs 16 and 17 extend, generally, upwardly from the points where the projections 30 engage the support 11 and extend somewhat outwardly relative to the alley 10 when the outer edge 26 of the projection 25 is in engagement with the side 14 of the alley 10, as shown in Fig. 4. The projection 25 extends outwardly and somewhat upwardly from the inner end of leg 16 to the point where it engages the side of the alley, while the projections 30 extend inwardly and somewhat downwardly from the ends of the end portions 20 to the points where they engage the sides of the support 11. The positioning of the device just described is clearly illustrated by Figs. 4 and 6. When the device has been arranged in position, as just described, it may be actuated to hold the alley and support 11 together, by driving the projection 25 into the side of the alley until it is completely embedded in the alley. When the projection 25 is completely embedded in the alley, the legs 16 and 17 are at, or close to, the side of the alley and the projections 30 are embedded in the support 11. Figs. 3 and 5 clearly illustrate the positioning of the device when actuated in the

manner just described. In actuating the device, that is in driving the projection 25 into the side of the alley, say by hammering, the alley and support are drawn closely together and the projections 30 automatically wedge or enter into the sides of the support 11. The drawings of the alley and support together and the wedging of the projections 30 into the support 11 is caused by the manner in which the legs 16 and 17 are connected and by the general arrangement, shape and relative positioning of the various parts of the device. The angle or positioning of the projection 25 relative to the other parts of the device cause it, when driven, to extend somewhat upwardly as well as inwardly into the side of the alley 10 thus drawing the entire device upwardly causing it to act as tongs so that the projections 30 grip or bite into the sides of the support 11 and resist the upward movement. The projections 30 upon entering the support 11 tend to extend inwardly and downwardly into it and thus tend to draw the entire device downwardly. Forcing the projection 25 into the alley against the resistance of the projections 30 causes the projections 30 to embed themselves in the support 11 and causes the alley and support to be drawn tightly together. When the device has been actuated or is in the position shown in Figs. 3 and 5 the projection 25 extends only slightly upwardly into the side of the alley 10 and therefore there is very little tendency for it to work out of the side of the alley. It will be obvious how the projections 30 cannot possibly work out of the support 11 so long as the projection 25 is in place in the alley 10. Under some circumstances it may be found desirable to assist the actuation of the device by driving the projections 30 into the support 11 as well as driving the projection 25 into the alley 10.

If at any time it is desired to release the two parts, that is, the alley and support, it is merely necessary to withdraw the projection 25 from the side of the alley whereupon the legs can be easily spread or swung out causing the projections 30 to withdraw from the sides of the support allowing the device to be lifted from around the support.

In the preferred form of the invention I form an opening or hole 40 in one, or in both, of the legs of the device so that the device can be held in place against the side of the alley by means of a screw or nail 41 in the manner illustrated in Figs. 3 and 5. It will be obvious how a nail can be very easily and quickly driven through a hole 40 in one of the legs and into the alley when the device is in place and how a nail thus driven through a hole 40 and into the side of the alley will very effectively hold the device in place and positively prevent its working loose even where the members held to-

gether are subjected to vibration and jarring. It will be understood, of course, that a nail or screw used to hold the device in position need only be comparatively small and does not have to be anything like as large as would be necessary to secure the members together if used without the device of the present invention.

From the foregoing description it will be readily understood how the device may be very easily and cheaply manufactured, how it can be very quickly and conveniently applied or removed, and how it will effectively draw and hold members solidly and securely together. It is to be understood, of course, that the proportions and designs of the device may be varied considerably from that herein specifically set forth to accommodate the particular circumstances under which the device is to be used or to fit the particular members which are to be held together. It may be pointed out that the present device is particularly strong and durable even though it is simple and inexpensive of manufacture and how it may be used numerous times. Devices made in accordance with the present invention may be advantageously used in structures which are temporary or in structures which are to be taken apart occasionally. For instance, devices of the present invention may be advantageously used in the construction of scaffolding in connection with stage scenery, etc.

Having described only a typical embodiment of my invention I do not wish to limit myself to the specific details hereinabove set forth but wish to reserve to myself any changes or variations that may appear to those skilled in the art or that may fall within the scope of the following claims.

Having described a preferred form of my invention, I claim:

1. In a device of the character described, two outwardly diverging legs pivotally connected at their inner ends, inwardly extending projections at the outer ends of the legs, and a transversely extending projection at the inner end of one of the legs.

2. In a device of the character described, two legs pivotally connected at their inner ends and diverging outwardly from the point of pivotal connection, a projection at the outer part of each leg extending toward the other leg, and a projection at the inner part of one of the legs extending in a direction transverse of the plane of the legs.

3. In a device of the character described, two legs pivotally connected at their inner ends and diverging outwardly from the point of pivotal connection, a projection at the outer part of each leg extending outwardly and toward the other leg, and a projection at the inner part of one of the legs extending in a direction transverse of the plane of the legs.

4. In a device of the character described, two legs pivotally connected at their inner ends and diverging outwardly from the point of pivotal connection, a projection at the outer part of each leg extending toward the other leg, and a projection at the inner part of one of the legs extending in a direction upwardly and transverse of the plane of the legs.
5. In a device of the character described, two legs pivotally connected at their inner ends and diverging downwardly from the point of pivotal connection, a projection at the outer part of each leg extending downwardly toward the other leg, and a projection at the inner part of one of the legs extending in a direction upwardly and transverse of the plane of the legs.
6. In a device of the character described, two legs pivotally connected at their inner ends and diverging outwardly from the point of pivotal connection, a wedge shaped projection at the outer part of each leg extending toward the other leg, and a projection at the inner part of one of the legs extending in a direction transverse of the plane of the legs.
7. In a device of the character described, two legs pivotally connected at their inner ends and diverging outwardly from the point of pivotal connection, a projection at the outer part of each leg extending toward the other leg, and a wedge shaped projection at the inner part of one of the legs extending in a direction transverse of the plane of the legs.
8. In a device of the character described, two legs pivotally connected at their inner ends and diverging outwardly from the point of pivotal connection, a sharp wedge shaped projection at the outer part of each leg extending toward the other leg, and a sharp wedge shaped projection at the inner part of one of the legs extending in a direction transverse of the plane of the legs.
9. In a device of the character described, two legs pivotally connected at their inner ends and diverging outwardly from the point of pivotal connection, a projection at the outer part of each leg extending toward the other leg, and a broad projection at the inner part of one of the legs extending in a direction transverse of the plane of the legs and disposed in a substantially horizontal plane.
10. In a device of the character described, two legs having pivotally connected inner portions and diverging downwardly from the point of pivotal connection and substantially vertical outer portions, a projection at the outer part of each leg extending toward the other leg, and a projection at the inner part of one of the legs extending in a direction transverse of the plane of the legs.
11. In a device of the character described, two outwardly diverging legs pivotally connected at their inner ends, inwardly extending projections at the outer ends of the legs, and an integral transversely extending projection at the inner end of one of the legs.

In witness that I claim the foregoing I have hereunto subscribed my name this 21st day of May, 1921.

ALEXANDER S. MATHERS.
